UNITED STATES PATENT OFFICE

92,490

DESIGN FOR A RANGE

Elmer D. Pellegrin, Des Plaines, Ill., assignor to
Cribben & Sexton Company, Chicago, Ill., a
corporation of Illinois

Application March 14, 1934, Serial No. 51,049

Term of patent 3½ years

To all whom it may concern:

Be it known that I, ELMER D. PELLEGRIN, a citizen of the United States, residing at 724 Arlington Avenue, Des Plaines, in the county of Cook, State of Illinois, have invented a new, original, and ornamental Design for a Range, of which the following is a specification, reference being had

to the accompanying drawing, forming a part thereof, in which:

The figure is a perspective view of the range showing my new design.

I claim:

The ornamental design for a range as shown.
ELMER D. PELLEGRIN.
